DESIGN FOR A COMBINED PERFUME
CONTAINER AND APPLICATOR

Henry J. Gittleson, Long Island City, N. Y., as-
signor to G. & M. Screw Products Co., Long
Island City, N. Y., a firm

Application May 7, 1946, Serial No. 129,414

Term of patent 3½ years

(Cl. D86—10)

To all whom it may concern:

Be it known that I, Henry J. Gittleson, a citizen of the United States, residing at Long Island City, in the county of Queens and State of New York, have invented a new, original, and ornamental Design for a Combined Perfume Container and Applicator, of which the following is a specification, reference being had to the accompanying drawing, forming a part thereof.

Fig. 1 is an elevational view of the combined perfume container and applicator in closed position, showing my new design.

Fig. 2 is a similar view with the cap removed.

Fig. 3 is a top plan view of the combined perfume container and applicator, shown in Fig. 2.

Fig. 4 is an elevational view of the cap.

I claim:

The ornamental design for a combined perfume container and applicator, substantially as shown.

HENRY J. GITTLESON.
